UNITED STATES PATENT OFFICE.

ARTHUR JOHN GRIMWOOD, OF STEVENSTON, SCOTLAND, ASSIGNOR TO IMPERIAL CHEMICAL INDUSTRIES, LIMITED, OF LONDON, ENGLAND.

SHELL AND THE LIKE.

Application filed January 17, 1928, Serial No. 247,468, and in Great Britain January 21, 1927.

This invention relates to fuse compositions and to fuses for shells, having time devices for regulating their explosion.

It is customary at the present time for 5 time devices for regulating the explosion of shells to consist of time rings into the grooves of which ordinary black powder is compressed at high pressure.

With modern guns, and especially those 10 used for anti-aircraft work, much difficulty is experienced owing to the time of burning of the powder columns varying very considerably when the shells are fired from high velocity guns, probably in part due 15 to the tendency for the burning to die out as a result of the high speed of rotation, and probably in part owing to the fact that the altitude reached by the shell is so great that a very greatly reduced pressure is 20 encountered. In extreme cases the burning of the powder is actually extinguished.

The object of the present invention is to provide a time regulator as free as possible of the disadvantages referred to above.

25 It has now been found that by the employment of a form of black powder in which the charcoal ingredient is replaced wholly or in part by cuprene, the solid high molecular polymerization product of acetylene 30 obtained when the latter is heated to a high temperature in the presence of a catalyst, the powder burns under reduced atmospheric pressure at speeds more closely approaching the normal than is the case 35 with ordinary black powder, and at very low pressures burns where ordinary black powders almost consistently fail. Its behaviour at high speeds of rotation is found also to be superior to that of ordinary black 40 powder.

The invention consists in a method and means for exploding shells or the like which comprises the ignition of a form of black powder in which all or part of the charcoal 45 ingredient of ordinary black powder is replaced by cuprene.

The invention also consists in a time device for regulating the explosion of shells or the like comprising one or more time 50 rings containing a form of black powder in which all or part of the charcoal ingredient of ordinary black powder is replaced by cuprene.

The invention also consists in time de- 55 vices with fuse compositions comprising a

form of black powder in which all or part of the charcoal ingredient of ordinary black powder is replaced by cuprene, substantially as described below.

Referring to the accompanying diagrammatic drawings:—

Figure 1 is a part sectional elevation of a time ring fuse such as may be employed in connection with the present invention.

Figure 2 is a section on the line 2—2 of Figure 1, looking in the direction of the arrows.

In carrying the invention into effect in the form illustrated by way of example, I provide a timing device *a* for a shrapnel shell, this timing device being of known construction and including an inner chamber *b* acting as a firing device and fuse magazine.

The timing device also includes a series of rings *c* having grooves *d* cut therein nearly the whole way round and provided with holes or passages *e* leading to the firing device or magazine chamber *b*. The grooves *d* are also connected by holes or passages *f*.

The grooves *d* are filled with a powder similar to ordinary fine grain black gunpowder except that in place of all or part of the usual charcoal ingredient, cuprene is employed.

This powder is firmly compressed at high pressure into the grooves *d* and the rings *c* are then mounted in the fuse head of the shell in the ordinary way.

In operation, as the powder is ignited at 90 one end of the grooves *d* the flame travels round until it comes to the hole leading to the next groove *d* and so on.

The rings *c* may be made of any suitable metal, for example brass or aluminium alloy, 95 and, if desired, especially where aluminium or aluminium alloys are employed, the channels may be lined with brass.

Shell time fuses as described above may be combined with percussion fuses.

Having now described my invention, what I claim as new and desire to secure by Letters Patent is:—

1. A time device for regulating the explosion of shells and the like including a 105 time ring containing a form of black powder in which at least part of the charcoal ingredient of ordinary black powder is replaced by cuprene.

2. A time device for regulating the ex- 110

plosion of shells and the like comprising a plurality of time rings containing a form of black powder in which at least part of the charcoal ingredient of ordinary black powder is replaced by cuprene.

3. A shell time fuse with ignition means comprising a time ring containing a form of black powder in which at least part of the charcoal ingredient of ordinary black powder is replaced by cuprene combined with a percussion fuse.

4. A time device for regulating the explosion of shells and the like comprising a ring containing aluminium, a brass liner in said ring and powder in said liner, said powder being a form of black powder in which at least part of the charcoal ingredient of ordinary black powder is replaced by cuprene.

In testimony whereof I have signed my name to this specification.

ARTHUR JOHN GRIMWOOD.
